(57) **CLAIM**

The ornamental design for an engine shroud, as shown and described.

DESCRIPTION

FIG. 1 is a front perspective view of a first embodiment of an engine shroud showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof; and,

FIG. 7 is a front perspective view of a second embodiment of an engine shroud showing our new design, it being understood that all other views of the second embodiment are substantially the same as FIGS. 1-6 of the first embodiment.

In the Figures, other engine components are shown in broken lines for illustrative purposes only, and form no part of the claimed invention.
